CONTROLLING APPARATUS FOR OIL BURNERS

Filed Sept. 2, 1927

UNITED STATES PATENT OFFICE

EDWARD I. VEITCH AND GEORGE N. BLANCHARD, OF PIEDMONT, CALIFORNIA

CONTROLLING APPARATUS FOR OIL BURNERS

Application filed September 2, 1927. Serial No. 217,168.

This invention relates to an electrically operated device for controlling the operation of oil burners.

The invention is primarily designed to provide an apparatus which operates automatically to control the rotor of a rotary oil burner, whereby the same is heated by the admission of the gas thereto, insuring the gasifying and combustion of the oil immediately on the same reaching the rotor of the burner at the starting of the same. It is also designed to insure the rotation of the rotor for a period of time after the oil flow thereto has been shut off, to discharge any remaining oil flow by centrifugal force therefrom, eliminating the liability of unburned oil depositing in a hard or gummy mass on the rotor head, and reducing to a minimum the clogging of the burner when a perforated or ported rotor is employed. Another of its objects is to provide an automatic means for igniting an oil burner and wherein if the burner does not ignite on its initial operation, the igniting operation is repeated at intervals until the ignition of the burner is accomplished. A further object is to provide a simple mechanism, capable of being cheaply manufactured and installed at a small cost, which will effectively carry out the previously set forth objects, and one which is adapted for connection with manual oil burners now in use to provide an automatic control therefor.

With the above mentioned and other objects in view, the invention consists in the novel construction and combination of parts hereinafter described, illustrated in the accompanying drawings and pointed out in the claims hereto appended; it being understood that various changes in the form, proportion, size and minor details of construction within the scope of the claims may be resorted to without departing from the spirit or sacrificing any of the advantages of the invention.

In the drawings:—

Fig. 1 is a view in elevation of one embodiment of our invention, this particular disclosure being designed for operating a hydraulically actuated gas fired rotor.

Fig. 2 is a view in side elevation of the structure illustrated in Fig. 1.

In the drawings, wherein like characters of reference designate corresponding parts—1 is a mounting panel, to the face of which is secured a block 2, the same having formed therein oil, gas and water channels, hereinafter described.

The block mounts a cylinder 3 with the base of which communicates a water channel 4, branching from a main water passage 5 extending through the block, the inlet end of which is indicated at 6, and the cylinder relief end at 7.

The main water passage 5 has a valve chamber 8 therein and at a point between the inlet channel and chamber 8 lateral passage 9 branches from the main passage 5 and connects with the water wheel of the conventional type associated with the rotor or plate of 70 the oil burner, not shown.

The block 2 is also provided with oil and gas channels 10 and 11, each connected at one end to a supply under pressure and at its other end the oil channel is connected with the burner and the gas channel also communicates with the burner, the latter being not illustrated.

Within the valve channel 8 is mounted a double faced conical valve 12 of the needle type adapted when moved downwardly to shut off the supply of water into the cylinder 3 and relieve the water pressure in the cylinder through the channel 7.

The valve 12 when raised closes the relief 7 from the cylinder 3 and opens the water supply 5 to the base of the cylinder through the restricted orifice A. The valve 12 is carried at the lower end of a stem 14, slideable in a guide 15, the stem at its upper end carrying 90 adjustable throw collars 16 between which lies one end of the lever 17.

In the cylinder 3 reciprocates a piston 18 the stem 19 of which carries a body 20 of sufficient weight to cause a downward movement of the piston within the cylinder on a release of the fluid pressure from within the cylinder. The stem 19 carries an arm 21 extended laterally therefrom, the latter moving longitudinally of a rod 22 between stop 100

collars 23 and 23'. The rod 22 extends upwardly from the lever 17 and pivotally connects at its upper end at 24 with one end of a trip lever 25, the ends of which are beveled at 26 and co-act with the upper ends of thermostatic bars 27 and 28, hereinafter more fully described. The lever 17 serves as an operating means for the valve 12, and to releasably retain the valve in either of its operated positions an anti-friction roller 29 on the end thereof rides over a pointed projection 30 on a spring held pawl 31. Between the end of arm 21 and collars 23 and 23' are positioned coiled compression springs 32, slidable on the 15 rod 22.

A reciprocating needle valve controls the passage of water from the branch 34 of inlet 6 to the pipe 35 leading to the water wheel, not shown.

20 Needle valves 36 and 37 control respectively the flow of gas through the channel 11 to the burner, not shown, and the flow of oil to the burner through channel 10. The stems of the respective valves 33, 36 and 37 operate 25 through guide stems 38, of the conventional type, and extend upwardly from the block 2 in substantially parallel relation.

30 Springs 39 act to normally force the valves 36 and 37 toward their seats while the spring 39 acts to normally unseat the valve 33. A lever 41 overlies the upper end of stem 33 and is acted on by arm 21 on stem 19 during the reciprocation of the piston 18. The stems of valves 36 and 37 at their ends pivotally 35 connect respectively with the levers 42 and 43 pivotally mounted on a common axis 44 with the lever 43 of a length slightly greater than that of lever 42, as clearly illustrated in Fig. 1. The levers 42 and 43 are operated to throw 40 valves 36 and 37 by the action of a plate 45 pivotally mounted at one end to the upper surface of arm 21, as at 46, with its free end projecting beyond the arm into the path of the levers. The plate is free to pivot upward- 45 ly from the arm 21 and held from swinging movement to a position below the plane of arm 21 by its contact with the upper surface of the arm.

50 Temperature controlled electric mechanism is employed for operating the controlling mechanism previously described, and its arrangement is as follows:—

Power is preferably taken from a regular 110 volt line through a transformer 46, one 55 output terminal of which connects through a lead 47, controlled by a switch 48 with the movable element of a thermostat member 49. The other transformer output terminal connects through lead 50 with a movable switch 60 blade 51 carried by the lever 43, near its fulcrum point 44. The thermostatic contact terminals 52 and 53 connect respectively with heating coils 54 and 55 surrounding the respective thermostatic bars 27 and 28, the latter being of the conventional laminated

type. From the coils extend the respective leads 56 and 57 connecting with the contact terminals 58 and 59 located adjacent to each other in spaced relation and adapted to be engaged by the movable switch blade 51 on lever 43.

The switch 48 is capable of being thrown to cut directly into the lead connecting with coil 54, thus directly connecting the coil with the power source and eliminating the thermo- 75 stat 49 and contacts 52 and 53.

As assembled in the drawing, the apparatus as described operates in the following manner:—

80 The temperature in the enclosure in which the thermostat 49 is located having dropped below the point of low setting of the thermostat, contact is made between 49 and 53, causing the current to heat bar 28, flexing the same and moves it from beneath the end of lever 85 25. This removal enables spring 32 bearing on collar 23 on the rod 22 to depress lever 17, raising valve 12 to the position shown in Figure 1, opening the water supply 6, and closing the relief of discharge. This action also 90 causes the opposite end of lever 25 to move upwardly and overlie the upper end of bar 27, as in the drawing, where it remains until the enclosure temperature rises above the point of high setting of the thermostat 49. 95 The opening of valve 12 admits water under pressure into the cylinder 3 through a restricted orifice, the size of the latter controlling the speed of admission of water into and the discharge of water from the cylinder. 100 The action of the water in cylinder 3 elevates piston 18 against the action of weight 20.

At the commencement of its upward movement, the pressure of weight 20 is removed from the lever 41, enabling spring 40 to actuate needle valve 33, admitting water to pipe 35 leading to the water wheel, not shown, which rotates the burner, also not shown.

105 Thus the first operation is to revolve the burner or burner rotor. As the piston 18 continues to rise, the plate 45 contacts with the edges of levers 42 and 43 and moves upwardly along the same, throwing the levers to operate or unseat their associated valves 36 and 37. The valve 36 operates preferably slightly in 110 advance of valve 37 to insure the admission of gas for the heating of the burner prior to the admission of oil thereto. The gas flame controlled by valve 36 is ignited by a pilot flame burning at all times near the burner, and 115 not herein illustrated. The operation of valve 36 in advance of valve 37 may be accomplished in many ways, the preferred form being to control the normal position of the lever 42 when the valve is closed, so that its edge will lie slightly in advance of the corresponding edge of lever 43.

120 As the piston 18 reaches approximately its limit of upward movement, plate 45 rides clear of the end of lever 42, permitting spring 125

39 to seat valve 36 and shut off the igniting gas flame of the burner. Plate 45 comes to a point of rest opposite the upper end of lever 43, holding the same outwardly and retaining the oil valve open. At this time the switch blade 51 is moved from contact with member 59 and has made contact with member 58.

Thus the supply of oil to the burner continues, as does the supply of power medium for operating the burner rotor plate or disk.

As the temperature in the enclosure in which the thermostat 49 is positioned reaches the point of high setting for the thermostat, a circuit is completed through 49 and 52 and coil 54 is heated, outwardly flexing bar 27, withdrawing its end from beneath lever 25. The pressure of spring 32 against the upper collar 23' on rod 22 upwardly moves the rod, causing lever 17 to move, moving roller 29 over projection 30. This operation also moves the right end of lever 25 upwardly over bar 28 to overlie the same. This operation depresses valve 12, shutting off inlet 5 to the cylinder and opening the relief connection between the cylinder and 7. The weight 20 causes a downward movement of piston 18 and stem 19, resulting in plate 45 pivoting on its fulcrum 46, permitting a gradual movement of lever 43 to the right, and the plate riding on the end of lever 42. The oil flow is thus shut off to the burner and a short time thereafter, when the piston reaches its lowermost point, the lever 41 is depressed by arm 21 against the action of spring 40 and shuts off the actuating power source to the burner rotor, but this does not take place until after the oil supply to this same member has been shut off, insuring the discharge of all oil from the rotor.

A safety circuit to insure the repeating of the burner igniting operation until such time as the burner ignites is provided, and the same operates in the following manner.

In the stack 60 through which products of combustion are carried, is positioned a thermostat 61 of the type in which the temperature controlled element 62 carries a movable contact terminal 63, which when the stack draft is cold engages with a contact 64 from which extends a lead 64' cut into the line connecting 52 and 54. A terminal 65 is engaged by the movable contact when the latter is pressed by the member 63, and from the terminal 65 extends a lead 66 connecting with one output take-off from the transformer between the transformer 46 and switch 48.

Thus should the piston 18 rise opening valves 36 and 37 and the burner fail to ignite, the circuit will remain complete, due to a cool stack through 64, 65, 58 and 51, as the lever 43 would be in elevated position. This circuit would heat coil 54 and actuate bar 27 to permit the piston to lower, controlling the various parts during its movement. The ther-

mostat 49 would be still in contact with 53, as the room temperature had not risen, and consequently the burner starting and igniting operation would again take place. As soon as sufficient heat rises in stack 60, member 61 is contracted, breaking this auxiliary circuit.

We claim:—

1. A mechanism for controlling the operation of a rotary oil burner, comprising an oil valve for controlling the supply of oil to the burner, a gas valve for controlling the supplying of a heating and igniting medium to the burner, a power valve for controlling the supply of power to the burner for rotating the same, a controlling means for all of said valves, electrically operated means for said controlling means for operating the latter on the starting of the burner to first open said power valve, then open said gas valve, and lastly open said oil valve, permitting the gas valve to close with said power and oil valves remaining open and on the extinguishing of the burner to first close the oil valve and lastly close the power valve.

2. A mechanism for controlling the operation of a rotary oil burner, comprising oil and gas channels connecting with the oil burner, valves controlling the passage of oil and gas therethrough, a hydraulic power supply connecting with the burner for rotating the same, a valve for controlling the hydraulic power supply to the burner, a cylinder and piston, a connection between the hydraulic power supply and the cylinder, a relief connection extending exteriorly of the cylinder, a valve controlling the passage of power medium selectively through said connections to cause the operation of the piston, electrically releasable means for retaining said valve in its operative position, means associated with the oil and gas valves and the valve controlling the power supply to the burner and operated by the reciprocation of the piston to cause the opening of said valve admitting power supply to the burner prior to the operation of the oil valve and the gas valve.

3. A mechanism for controlling the operation of a rotary oil burner, comprising a valve controlled channel through which oil is fed to the burner, a power source valve means for controlling the delivery of a portion of the power from said source to the burner for its rotation, means actuated by another portion of power from said source for opening said power and oil controlling valves in sequence, a controlling valve for actuating said means, a temperature controlled main electric circuit for operating said control valve and for retaining the same in its operated position.

4. A mechanism for controlling the operation of a rotary oil burner, comprising a valve controlled channel through which oil is fed to the burner, a power supply valve means for controlling the delivery of a portion of the power from said supply to the burner for its

rotation, means actuated by a portion of the power from said supply for opening said power and oil valves in sequence, a controlling valve for actuating said means, a temperature control main electric circuit for operating said control valve and for retaining the same in its operated position, an auxiliary circuit connected with said main circuit, means within said auxiliary circuit operated by the heat of combustion from the burner for causing successive operations of said control valve to open and close said power and oil valves until heat is generated by said burner.

In testimony whereof we have signed our names to this specification.
